UNITED STATES PATENT OFFICE

1,970,355

SUCTION CLEANER

Averill M. Bennett, Lusk, Wyo.

Application March 26, 1934, Serial No. 717,481

1 Claim. (Cl. 15—6)

The present invention relates to new and useful improvements in suction cleaners for floors and floor coverings of the type including a suction nozzle having mounted therein a motor driven rotary brush and has for its primary object to provide, in a manner as hereinafter set forth, a cleaner of this character comprising a novel construction and arrangement of swinging beater operable in the nozzle forwardly of the brush.

Another important object of the invention is to provide a suction cleaner including a beater forwardly of the brush, together with novel means for operatively connecting said beater to said brush for actuation thereby.

Other objects of the invention are to provide a suction cleaner of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a side elevation with parts broken away, of a suction cleaner embodying my invention.

Figure 2 is a view in bottom plan of the forward portion of the cleaner.

Figure 3 is a vertical sectional view, taken substantially on the line 3—3 of Figure 2.

Figure 4 is a detail view in perspective of the beater.

Figure 5 is a detail view in front elevation of one of the elements which operatively connect the beater to the brush.

Figure 6 is an elevational view of one end portion of the brush having mounted thereon an eccentric for actuating the beater.

Figure 7 is a view in end elevation of the brush.

Referring now to the drawings in detail, it will be seen that the reference numeral 1 designates a suction nozzle having journaled transversely therein a rotary brush 2. The brush 2, as usual, is operable in the rear portion of the mouth or inlet opening of the nozzle 1.

The rotary brush 2 is operatively connected by an endless belt 3 to a pulley 4 which is fixed on the shaft of an electric motor 5, said shaft, as usual, also having mounted thereon a rotary suction fan 6 which is operable in the chamber 7.

The reference numerals 8, 8 designate a pair

of levers which are pivotally mounted for swinging movement in a vertical plane, as at 9, on the side walls of the suction nozzle 1 forwardly of the rotary brush 2. Extending between the forward end portions of the levers 8 is a beater bar 10 which is operable in the mouth or inlet opening of the nozzle 1, as will be understood. Eccentrics 11 are fixed on the ends of the rotary brush 2 and the levers 8 are operatively coupled thereto through the medium of connectors which are designated generally by the reference numeral 12, said connectors including rings 13 journaled on the eccentrics 11 and from which depend arms 14 which are pivotally connected to the rear end portions of said levers 8. This is illustrated to advantage in Figure 3 of the drawings.

It is believed that the operation of the invention will be readily apparent. With the fan 6 in operation the floor covering, which is designated by the reference numeral 15 in Figure 1 of the drawings, is drawn upwardly toward the suction nozzle 1 where it is engaged by the rotating brush 2. As the brush rotates swinging movement is imparted to the levers 8 thus rapidly moving the beater bar 10 upwardly and downwardly for effectively beating the floor covering in advanced of the brush.

It is believed that the many advantages of a suction cleaner constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed.

What is claimed is:—

In a suction cleaner, a suction nozzle and a motor driven rotary brush operable in said nozzle, eccentrics fixed on the ends of the rotary brush, a pair of levers pivotally mounted intermediate their ends, on the side walls of the nozzle forwardly of the brush, a beater bar extending between the forward end portions of the levers, and means operatively connecting said levers to the eccentrics for actuation thereby, said means including rings journaled on the eccentrics, and arms projecting from the rings and pivotally connected to the rear end portions of the levers.
